UNITED STATES PATENT OFFICE

2,541,119

ELECTRIC IRON

Charles H. Sparklin, Chicago, Ill., assignor to
Birtman Electric Company, a corporation of
Illinois

Original application May 9, 1945, Serial No.
591,911. Divided and this application October
3, 1946, Serial No. 700,957

5 Claims. (Cl. 219—25)

1

This invention relates to a heat regulating iron and more particularly to a sadiron in which heat indicating means are provided for indicating the setting of the thermostat at a point remote from the means of adjusting the same.

In my copending application, Serial No. 535,645, filed May 15, 1944, now Patent #2,457,185 issued Dec. 28, 1948 a thermostatic adjustment is positioned in a part of the iron convenient to the fingers with the indicia placed with an indicator in a position on the iron convenient to the eye. This application also includes superimposition of the setting indicator and the temperature indicator so that the operator may ascertain at a single glance how the actual temperature of the iron corresponds to the pre-determined setting.

In the present invention I have perfected a new iron having a thermostatic control member which does not require movement through a non-operating temperature range of the iron. When the "off" position is reached, the contact points of a switch are forcibly separated and maintained separated. This enables almost the entire range of the thermostatic adjustment to be used for adjusting the iron within the operating range. The abrupt change is preferably accomplished by having the control move from off position to high position and thence to low, but the off position may be at the low end, although this is less desirable.

The invention will be described in considerable detail as related to the embodiment of the same set out in the accompanying drawings. Of the drawings, Fig. 1 is a side elevation of an iron embodying the feature of this invention; Fig. 2 is a plan view of the iron of Fig. 1; Fig. 3 is a side elevation, partially in section; Fig. 4 is a section taken along line 4—4 of Fig. 3; Fig. 5 is a section taken along line 5—5 of Fig. 3; Fig. 6 is a section taken along line 6—6 of Fig. 3; and Fig. 7 is a section taken along line 7—7 of Fig. 3.

As shown in the drawings, the iron 10 comprises a sole plate 11 and a hood 12 which together define the body portion of the iron, a handle support 13, a handle 14 containing openings 48 in either side at the rear for positioning an electric cord, and a control knob 15. The usual form of snap acting thermostat 16 is provided in the body of the iron and is affixed to the sole plate 11. This thermostat may be adjusted by a movement of the post 17. The thermostatic control includes a make and break switch having contact points 18. One of these points is mounted on a section of spring steel 19, while the other point is mounted on a short bimetal thermostat element 20.

5

2

This second bimetal element is fastened to another section of spring steel 21. The second bimetal element 20 provides sharper control for the switch for when it is heated it curls downward in opposite direction to that of the first bimetal element 16. This construction results in a thermostatic switch in which very sharp control is provided.

The thermostatic switch is controlled by rotation of the control knob 15 in the following manner. The knob 15 has a central opening in which an internal sleeve 22 is anchored. Within this sleeve is a square nut 23 which is thus turned by turning of the knob 15. This nut contains a threaded post 24 which is rotatably journaled in the sole plate at its bottom and which has a head 25 fastened within a plate 26 in the handle.

The square nut 23 is provided at its base with a collar 27 having a groove 28. A broken rocker arm 29 is pivotally mounted in a bracket 30. This rocker arm is engaged at its front end by the sides of the groove 28. The other end of the rocker arm bears against a post 31 that is fastened to the lower spring steel arm 19 which carries a contact point 18 for the make and break switch. Thus the post 31 serves to position the switch relative to the first bimetal thermostat element 16. The broken rocker arm 29 is constructed so that it acts as a rocker arm in one direction only. This is provided for by having the rocker arm in two sections, each mounted on the same pivot, but with the front section 32 terminating around the rocker in a yoke, the ends of which bear upon the top of the rear section 33 of the rocker arm. The positioning of the rocker arm positions the switch relative to the first bimetal thermostat element 16 which controls the temperature at which the iron operates.

This positioning is accompanied by rotation of the knob 15. When the knob 15 is rotated, the square nut 23 is moved up or down on the post 24. This moves the collar 27 and thus positions the rocker arm 29 which operates as a rocker only when the collar 27 moves upwardly. When the collar is moved in a downward direction, the rear of the rocker arm is kept in proper position by means of the spring steel section 19 pushing against the rocker arm through post 31. Such a construction is provided so that the rear portion 33 of the rocker arm may serve as a lever fulcrum at one end around the rocker arm pivot. It functions as a lever when the free end of the rear portion is pushed down. The purpose of this construction will be explained in greater detail hereinafter.

The setting of the thermostat is shown by the

indicator 34, the end of which points to the indicia 35 mounted below the handle. The end of the indicator 34 appears through an arcuate opening 36 in the body of the iron. In the particular form shown, this opening also passes through the handle support 13, the indicator 34 is operated simultaneously with the setting of the thermostat by means of a gear train 37 connected to the square nut 23. A ring gear 38 having a square central opening is slidably mounted on the square nut 23 and meshes with the larger circumference of a flat ring reducing gear 39. The smaller circumference of the gear meshes with a toothed arcuate member 40 attached to the mounting 41 that bears the indicator 34. This mounting 41 is concentric with the shaft 42 and is designed to turn independently of the shaft.

The temperature indicator preferably comprises a thermostatic coil 43 secured to the sole plate 11 of the iron in a central location. This coil may be a conventional bimetal material in spiral shape adapted to expand and contract as it heats and cools. At the inner end of the coil there is located a post 42 that is rotatable under the influence of the bimetal coil. The base of the post 42 is rotatably journaled in the sole plate. As a result when the temperature of the sole plate rises, the coil expands and turns the shaft. The temperature indicating means 44 is secured to the neck of the shaft 42 and rotates therewith. This means comprises a ring 45 having its circumferential portion underlying the opening 36 and the point of the setting indicator 34. The ring may be painted appropriately, for example, with a red zone, a yellow zone, and a green zone, and is also marked so that whenever the yellow zone underlies the temperature setting the temperature of the iron is the temperature indicated. On the other hand when the red zone underlies the setting indicator the temperature of the iron will be above that required for a particular operating condition, and when the green zone underlies the pointer the temperature of the iron will be below that suitable for the preferred operating conditions. This method of marking and the way in which the setting indicator and the thermometer may be calibrated is explained in detail in my copending application referred to hereinabove.

On the rear section 33 of the broken rocker arm there is mounted an upwardly extending arm 49 projecting through an opening 50 in the support plate for the reducing gear 39 (Figure 7). The upwardly extending portion is located so that when the control knob 15 is turned to a position corresponding to a high temperature the larger circumference of the ring reducing gear 39 contacts the inclined plate 50 and pushes it down, thereby preventing locking of the parts. This serves to push the rear section 33 of the broken rocker arm down and break the contact of the control switch. It can be seen that when the rear portion of the broken rocker arm is used in the above manner it acts as a lever fulcrumed at the point of pivot of the broken rocker arm.

After the new iron has been built and before it has been put in operation it should be synchronized so that the temperature indicator will coincide with the thermostat setting. This can conveniently be done by means of a headless screw 51 positioned in the hub 52 of the temperature indicating means 44. The screw presses against post 42 that is attached to the bimetal thermostat 43 after the parts have been synchronized.

The knob 15 which is used to control the operating temperature of the iron, has a finger contacting portion 46 extending beyond the main body portion of the knob. This extended portion is separated from the rest of the knob by deep circular grooves 47 on either side which serve to keep the finger contacting portions 46 cool.

This application is a division of my copending application Serial No. 591,911, filed May 4, 1945.

The foregoing detailed description has been given for clearness of understanding only, and no necessary limitations should be understood therefrom.

I claim:

15. In an electric iron having a handle and a body portion, a thermostat in the body adjacent the heating element, a switch operated by said thermostat for turning electric current on and off, and a finger-manipulative rotatable member on said handle for adjusting the switch to any desired setting, a broken rocker arm operable as a rocker arm in one direction only for positioning said switch, one end of said rocker arm operating on said switch when the other end is adjusted by said rotatable member, setting-indicating means operated by said rotatable member through a gear train, means operated by said rotatable member also through said gear train for displacing the switch end of said rocker arm to disengage the switch when said rotatable member is turned to a position corresponding to a very high temperature, the broken rocker arm separating when moved in this direction so that the switch end is a lever fulcrumed at one end.
20. The electric iron of claim 1 wherein said means for displacing the switch end of said rocker arm comprises a portion of said gear train.
25. In an electric iron having a handle and a body portion, a thermostat in the body adjacent the heating element, a switch operated by said thermostat for turning electric current on and off, and a finger-manipulative rotatable member on said handle for adjusting the switch to any desired setting relative to said thermostat for regulating the operating temperature in said iron, a broken rocker arm operable as such in one direction only, one end of said rocker arm being positioned by movement of the said rotatable member to position said switch relative to the thermostat, setting-indicating means also operated by said rotatable member through a gear train, and an inclined bearing plate on the end of the switch arm of the broken rocker and adapted to be engaged by a portion of the gear train to disconnect the switch when said rotatable member is turned to a position corresponding to a very high temperature, the broken rocker separating when moved in this direction so that the switch end is a lever fulcrumed at the rocker axis of the rocker.
30. In an electric iron having a handle and a body portion and a heating element, a thermostat in the body portion adjacent the heating element, a switch operated by said thermostat for turning electric current on and off and a finger-manipulative rotatable member for adjusting the switch to a desired setting, lever means for bearing directly against said switch and operated by said rotatable member for said adjusting of the switch, setting-indicating means also operated by said rotatable member and including a gear train, and rigid means operated by said rotatable member through said gear train for displacing the switch end of said lever means to disengage the
35. In an electric iron having a handle and a body portion, a thermostat in the body adjacent the heating element, a switch operated by said thermostat for turning electric current on and off, and a finger-manipulative rotatable member on said handle for adjusting the switch to any desired setting relative to said thermostat for regulating the operating temperature in said iron, a broken rocker arm operable as such in one direction only, one end of said rocker arm being positioned by movement of the said rotatable member to position said switch relative to the thermostat, setting-indicating means also operated by said rotatable member through a gear train, and an inclined bearing plate on the end of the switch arm of the broken rocker and adapted to be engaged by a portion of the gear train to disconnect the switch when said rotatable member is turned to a position corresponding to a very high temperature, the broken rocker separating when moved in this direction so that the switch end is a lever fulcrumed at the rocker axis of the rocker.
40. In an electric iron having a handle and a body portion and a heating element, a thermostat in the body portion adjacent the heating element, a switch operated by said thermostat for turning electric current on and off and a finger-manipulative rotatable member for adjusting the switch to a desired setting, lever means for bearing directly against said switch and operated by said rotatable member for said adjusting of the switch, setting-indicating means also operated by said rotatable member and including a gear train, and rigid means operated by said rotatable member through said gear train for displacing the switch end of said lever means to disengage the
45. In an electric iron having a handle and a body portion and a heating element, a thermostat in the body portion adjacent the heating element, a switch operated by said thermostat for turning electric current on and off, and a finger-manipulative rotatable member on said handle for adjusting the switch to any desired setting relative to said thermostat for regulating the operating temperature in said iron, a broken rocker arm operable as such in one direction only, one end of said rocker arm being positioned by movement of the said rotatable member to position said switch relative to the thermostat, setting-indicating means also operated by said rotatable member through a gear train, and an inclined bearing plate on the end of the switch arm of the broken rocker and adapted to be engaged by a portion of the gear train to disconnect the switch when said rotatable member is turned to a position corresponding to a very high temperature, the broken rocker separating when moved in this direction so that the switch end is a lever fulcrumed at the rocker axis of the rocker.
50. In an electric iron having a handle and a body portion and a heating element, a thermostat in the body portion adjacent the heating element, a switch operated by said thermostat for turning electric current on and off and a finger-manipulative rotatable member for adjusting the switch to a desired setting, lever means for bearing directly against said switch and operated by said rotatable member for said adjusting of the switch, setting-indicating means also operated by said rotatable member and including a gear train, and rigid means operated by said rotatable member through said gear train for displacing the switch end of said lever means to disengage the
55. In an electric iron having a handle and a body portion and a heating element, a thermostat in the body portion adjacent the heating element, a switch operated by said thermostat for turning electric current on and off, and a finger-manipulative rotatable member on said handle for adjusting the switch to any desired setting relative to said thermostat for regulating the operating temperature in said iron, a broken rocker arm operable as such in one direction only, one end of said rocker arm being positioned by movement of the said rotatable member to position said switch relative to the thermostat, setting-indicating means also operated by said rotatable member through a gear train, and an inclined bearing plate on the end of the switch arm of the broken rocker and adapted to be engaged by a portion of the gear train to disconnect the switch when said rotatable member is turned to a position corresponding to a very high temperature, the broken rocker separating when moved in this direction so that the switch end is a lever fulcrumed at the rocker axis of the rocker.
60. In an electric iron having a handle and a body portion and a heating element, a thermostat in the body portion adjacent the heating element, a switch operated by said thermostat for turning electric current on and off and a finger-manipulative rotatable member for adjusting the switch to a desired setting, lever means for bearing directly against said switch and operated by said rotatable member for said adjusting of the switch, setting-indicating means also operated by said rotatable member and including a gear train, and rigid means operated by said rotatable member through said gear train for displacing the switch end of said lever means to disengage the
65. In an electric iron having a handle and a body portion and a heating element, a thermostat in the body portion adjacent the heating element, a switch operated by said thermostat for turning electric current on and off and a finger-manipulative rotatable member for adjusting the switch to a desired setting, lever means for bearing directly against said switch and operated by said rotatable member for said adjusting of the switch, setting-indicating means also operated by said rotatable member and including a gear train, and rigid means operated by said rotatable member through said gear train for displacing the switch end of said lever means to disengage the
70. In an electric iron having a handle and a body portion and a heating element, a thermostat in the body portion adjacent the heating element, a switch operated by said thermostat for turning electric current on and off and a finger-manipulative rotatable member for adjusting the switch to a desired setting, lever means for bearing directly against said switch and operated by said rotatable member for said adjusting of the switch, setting-indicating means also operated by said rotatable member and including a gear train, and rigid means operated by said rotatable member through said gear train for displacing the switch end of said lever means to disengage the
75. In an electric iron having a handle and a body portion and a heating element, a thermostat in the body portion adjacent the heating element, a switch operated by said thermostat for turning electric current on and off and a finger-manipulative rotatable member for adjusting the switch to a desired setting, lever means for bearing directly against said switch and operated by said rotatable member for said adjusting of the switch, setting-indicating means also operated by said rotatable member and including a gear train, and rigid means operated by said rotatable member through said gear train for displacing the switch end of said lever means to disengage the

switch when said rotatable member is turned to a position at one end of its path of movement.

5. The electric iron of claim 1 wherein said rigid means includes an extending portion on the switch end of said lever means normally positioned to be contacted by said gear train when said lever means is displaced to disengage the switch.
